Primary Examiner — Mark A Goodwin*(74) Attorney, Agent, or Firm* — Birch, Stewart, Kolasch & Birch, LLP(57) **CLAIM**

The ornamental design for a cab for a construction machine, as shown and described.

DESCRIPTION

FIG. 1 is a first perspective view of a cab for a construction machine showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the cab for a construction machine in which the design is embodied that are not considered part of the claimed design.

1 Claim, 8 Drawing Sheets(56)
